UNITED STATES PATENT OFFICE

172,061

TELEPHONE HANDSET SUPPORTING DEVICE

Herman H. Renneker, San Diego, Calif.

Application November 6, 1952, Serial No. 22,166

Term of patent 14 years

(Cl. D26—14)

To all whom it may concern:

Be it known that I, Herman H. Renneker, a citizen of the United States, residing at San Diego, county of San Diego, State of California, have invented a new, original, and ornamental Design for a Telephone Handset Supporting Device, of which the following is a specification, reference being had to the accompanying drawing, forming a part hereof.

Figure 1 is a plan view of a telephone handset supporting device embodying my new design;

Figure 2 is an edge elevational view thereof;

Figure 3 is a face view thereof, with the shoulder bracket broken away for the convenience of illustration; and

Figure 4 is a perspective view thereof, with the

shoulder bracket omitted for convenience of illustration.

The dominant features of my design reside in those portions shown in full lines.

The dot-dash showing of a telephone handset in Figure 2 is for purposes of illustration only.

I claim:

The ornamental design for a telephone handset supporting device, as shown and described.
